UNITED STATES PATENT OFFICE.

HENRY W. O'NEILL, OF ELMHURST, NEW YORK, ASSIGNOR TO WESTERN ELECTRIC COMPANY, INCORPORATED, OF NEW YORK, N. Y., A CORPORATION OF NEW YORK.

COMPOSITE RINGER CIRCUIT.

Application filed October 22, 1924. Serial No. 745,089.

This invention relates to composite ringer sets for relaying low frequency currents into currents of high frequency and vice versa.

5 Composite ringer sets are quite generally interposed between a line and a switchboard on composited, repeatered and other similar line circuits, and serve to prevent low frequency signaling or ringing currents from 10 reaching telegraph apparatus on composited circuits, and also to apply current at higher frequencies to telephone circuits in order that the current may traverse the telephone circuits without excessive attenuation. A standard type of composite ringer set now in general use, is adapted to relay 15 the usual switchboard ringing current of 16 or 20 cycles per second, to current at 135 cycles per second at the opposite or line 20 side of the set, while inversely 135 cycle current incoming at the line side of the set is relayed to 16 or 20 cycle current at the switchboard side of the set.

Heretofore, it has been the practice to 25 employ sources of alternating current which comprise equipment or units separate and distinct from the composite ringer sets themselves. For example, for ringing in one direction, the application of current 30 from a 16 or 20 cycle source effects the response of relays to switch the line circuit from the switchboard circuit to a source of 135 cycle current, while for signaling in the opposite direction, current from a 135 cycle 35 source effects the response of other relays to switch the switchboard leads from the line to a source of 16 or 20 cycle current.

With the composite sets, as hereinbefore described, dependent upon separate source 40 of ringing current at the sets, it has not been possible to employ composite ringers except where such separate sources of current are available. Thus the use of such sets has been limited to such points where the 45 traffic load is heavy enough to warrant the installation of ringing generators. In accordance with the present invention, it is proposed to dispense with the separate sources of current and to provide that the 50 receiving relays may at proper times also serve as vibrators to effect the generation of alternating current at corresponding frequencies for carrying out the necessary signaling operations. The composite set is 55 thus rendered complete within itself and en-

ables the use of the set at any isolated point or at points where, due to lower traffic loads during the night, Sundays or at other times, it becomes inadvisable to maintain the power equipment in continuous operation. 60

It is the object of the present invention to provide a composite ringer set which shall be complete within itself, independent of outside sources of ringing current, and economical to install and operate. 65

The object of the invention is attained through the employment of a vibrator relay of a type which short circuits its own windings. Vibrators of this type are free from contact chatter, are substantially unaffected 70 by current overloads, have little or no tendency to spark at the contacts, are easily adjusted, and have large energy output, as distinguished from vibrators of the interrupter type which have heretofore been 75 proposed. The vibrator relay is arranged in the composite set in such a manner that it operates efficiently at certain times as a current responsive device and at other times as a current generating device. 80

It is believed that the invention will best be understood from a consideration of the drawings and the following detailed description thereof:

Fig. 1 shows a composite ringer set in 85 which a transformer is employed for connecting the vibrator relay with an outgoing line, the transformer being common to a plurality of ringer sets.

Fig. 2 shows a composite ringer set employing an alternating current vibrator relay which is inductively coupled to the outgoing line both when the relay is serving as a generating and as a responsive device. 90

Fig. 3 taken in connection with the portion of Fig. 2 to the left of the dot and dash line shows a modification of the set shown in Fig. 2, condensers being used as an inductive coupling between the vibrator relay and the outgoing line. 95

Fig. 4 shows a further modification in which a retardation coil serves as a coupling between the vibrator relay and the outgoing line and also as retardation in the 100 20 cycle and 135 cycle bridges of the set. 105

Fig. 5 shows a composite set arranged to receive 135 cycle current from the outgoing line and repeat 20 cycle current to the switchboard line and to receive 20 cycle current from the switchboard line and repeat 110

135 cycle current to the outgoing line, vibrator relays serving as generating devices for both frequencies of current.

Fig. 6 shows a composite set arranged 5 with a high pass filter for conveying voice currents around the relays of the set.

Throughout the several figures of the drawing, the same numerals have been applied as far as possible to similar pieces of 10 apparatus disclosed in the several figures.

Referring particularly to Fig. 1, a line circuit is shown at 1-2, outgoing from the composite set and a switchboard line 3-4 extending from the set to a switchboard of 15 an exchange system. Inasmuch as the invention is not concerned with the particular structure and operation of the outgoing line and switchboard, they have not been disclosed herein. A source of 20 cycle current 20 is shown at 5 and a vibrator relay at 6 which is capable of responding to 135 cycle current incoming over the line 1-2 and of generating current at 135 cycles for transmission over line 1-2. A transformer 11 common 25 to a plurality of composite sets is provided for controlling the relays 6 of such sets in converting direct current into alternating current at the desired frequency.

In the operation of the composite set 30 shown in Fig. 1, low frequency signaling current of, for example, 20 cycles applied to the switchboard line 3-4, flows over conductor 3, the upper back contact of switching relay 7, through the retardation coil 12, condenser 13, alternating current relay 9, which is adjusted to respond to signaling current of 35 20 cycles, lower back contact of relay 7 to the conductor 4. Relay 9 responds, closing a circuit from battery through the winding 40 of switching relay 8, winding of relay 14, contact of relay 9 to ground at the back contact of relay 10. The energization of relay 8 disconnects the outgoing line 1-2 from the talking conductors of the set and connects the line 1-2 to the right winding of 45 common transformer 11. Relay 14 opens the circuit extending through relay 10 to prevent its operation at this time and establishes a circuit for the vibrator relay 6, which 50 extends from battery through the left windings of the transformer 11, the intermediate front contact of relay 14, both windings of relay 6 in series, to ground at the upper front contact of relay 14. Relay 6 energizes in 55 this circuit and at its contacts closes a shunt about its own windings, extending from ground at the contacts of relay 6 through the lower and intermediate front contacts of relay 14, both windings of relay 6 to ground 60 at the upper front contact of relay 14. As soon as this shunt is effective, relay 6 de-energizes. Thus, relay 6 continues to energize and deenergize in a vibratory manner so long as relay 14 remains operated. The 65 current changes thus set up in the left wind-

ings of transformer 11, are induced into the right winding of the transformer and transmitted to the line 1-2. A condenser 15 connected in shunt to a portion of the windings of relay 6 through the intermediate front contact of relay 14, serves to adjust the speed at which the tuned reed armature of relay 6 may tend to operate, while the relay is serving as a vibrator, the value of condenser 15 being such as will bring the frequency of 75 operation of the armature of relay 6 to 135 cycles.

To protect the contacts of relay 6 against the possibility of sparking, a resistance 17 and condenser 16 are connected to ground in 80 parallel with the ground connection through the relay contacts, through the lower front contact of relay 14. A condenser 19 in series with resistance 18 is bridged around the right winding of transformer 11 as an artificial load for steadyng and insuring uniformity of operation of the vibrator relay 6 of any composite set, irrespective of whether one or several sets may be connected at one and the same time to receive signaling current from the common transformer 11.

Since, as the multiple connections indicate, all vibrator relays 6 receive current in 95 parallel through the left windings of common transformer 11 and through contacts of associated relays 14, it follows that whenever one of the relays 6 is operated as a vibrator and its windings are thus short circuited through its contacts at that instant, no other relay 6 may receive current. It 100 therefore follows, that the relays 6 may receive energy only during such instants as all vibrators may be restored or with their respective contacts open, and all relays will be short circuited during the periods that the contacts of any relay may remain closed. As a consequence, the resulting 135 cycle 105 current produced in and supplied by the transformer 11 will be of even phase irrespective of whether one or more vibrator relays may be in action at the same time.

When a signaling current of 135 cycles is 110 incoming to the composite set, this current flows over conductor 1, the upper back contact of relay 8, retardation coil 12, condenser 20, upper back contact of relay 14, windings of relay 6, middle lower back contact of relay 14, lower back contact of relay 8 to conductor 2. The response of relay 6 to this current, intermittently closes the circuit extending through the contacts of relay 6 and the lower back contact of relay 14 through the winding of relay 10, causing the operation of relay 10 and the consequent operation of relay 7. Relay 10 in operating also removes ground from the operating circuit of relay 14 to insure that the latter relay may not be capable of operation at this time. Relay 7 upon operat-

ing, opens the normal connection of the switchboard line 3—4 to the talking conductors of the set, and connects the line to the 20 cycle source 5 of signaling current for operating any suitable signal at the switchboard. A condenser 21 is placed in bridge of all or a major portion of the winding of relay 10 for the purpose of enabling relay 10 to maintain its armature attracted during the half cycle periods during which the contacts of relay 6 are open, so that the application of current from the source 5 to the line 3—4 is maintained steady during the entire period when 135 cycle current is being applied over the line 1—2 to the relay 6. As soon as signaling is completed in either direction, and relays 7 and 8 are both in an unoperated condition, a talking circuit is established between the line 1—2 and the line 3—4 over the back contacts of these relays and the heavy conductors.

The modification shown in Fig. 2 is similar to that shown in Fig. 1 with the exception that the vibrator relay 6 is inductively connected to the line 1—2 through a transformer 22 which is individual to the composite set, the relay being inductively connected to the line 1—2, both when it is functioning as a vibrator for generating current and as a responsive device. On outgoing signals, relay 9 functions in the manner previously described in connection with Fig. 1 and closes the circuit of switching relay 8. Switching relay 8 upon energizing disconnects the limbs of line 1—2 from the talking conductors extending through the composite set, opens the circuit extending to the relay 10 to prevent this relay from falsely functioning at this time and prepares a shunt path around the windings of relay 6. Relay 9 also closes an operating circuit for the vibrator relay 6, extending from battery through the left winding of transformer 22, both windings of relay 6 to ground at the upper contact of relay 9. With relays 8 and 9 operated, as soon as relay 6 energizes, it shunts its own windings by a circuit extending from ground at its own contacts, through the lower front contact of relay 8, the windings of relay 6 to ground at the upper contact of relay 9. Relay 6 therefore functions as a vibrator relay so long as relay 9 remains energized, the surges of current set up in the left winding of transformer 22, being inductively transmitted through the right winding of this transformer and condenser 23 to the line 1—2. The resistance 17 and condenser 16 serve to prevent sparking at the contacts of relay 6, and condenser 15 which is bridged about one winding of relay 6 through the lower contact of relay 9, serves to tune the relay 6 to a vibratory frequency of 135 cycles.

On an incoming call, 135-cycle current ap-

plied to conductors 1—2 flows through condenser 23 and the right winding of transformer 22 and inductively operates relay 6, the induced current flowing from the left winding of transformer 22, through both windings of relay 6 and through condenser 20. Relay 6 in response to the 135-cycle current, establishes a circuit for relay 10 extending from battery through the winding of relay 10, the lower back contact of relay 8 to ground at the contact of relay 6. Relay 10 responds to this current being held operated during half cycles when the contacts of relay 6 are opened, by discharges from the condenser 16, and establishes an obvious shunt around the winding of relay 24. Relay 24 thereupon deenergizes closing the circuit of relay 7 which in turn disconnects the switchboard line 3—4 from the talking conductors of the composite set, and connects this line to the 20-cycle generator 5. As indicated by the conventional markings, the relay 7 is both slow to release and slow to operate, and relay 8 is slow to release. Such characteristics are to insure against false signals which might result from current surges in combined telephone and telegraph working, and also to insure that premature release of the relays, such as relay 8, may not take place under fluctuations of signaling current during the transmission of a signal.

Fig. 3 when considered in connection with that portion of Fig. 2 to the left of the dot and dash line illustrates a modification of the invention in which the vibrator relay 6 is inductively coupled to the outgoing line 1—2 through condensers, both when it is functioning as a generating device and as a responsive device. In response to outgoing signaling current of 20-cycles frequency from the switchboard line 3—4, relay 9 operates, this relay at this time being bridged across the talking conductors of the set through the condenser 13 and one winding of the retardation coil 25. Relay 9 in operating closes an obvious circuit for relay 8, which in turn, disconnects the line 1—2 from the talking conductors of the set, opens the circuit extending through the winding of relay 10 to prevent its operation at this time, and closes the circuit of the vibrator relay 6. The circuit for relay 6 may now be traced from battery, resistance 28, lowermost front contact of relay 8, both windings of relay 6, uppermost contact of relay 8, resistance 29 to ground. Relay 6 upon energizing short-circuits its windings over a circuit extending from its contacts over the two lower front contacts of relay 8, both windings of relay 6, the upper contact of relay 8, back to the contacts of relay 6. Relay 6 thereupon deenergizes and thereafter continues to operate in a vibratory manner so long as relay 9 remains energized.

Surges in the energizing circuit of relay 6 are then transmitted to the line 1-2, through the condensers 26 and 27, respectively, which join the opposite terminals of relay 6 with conductors 1 and 2 through front contacts of relay 8. Each time the contacts of relay 6 separate, potential from the battery by way of resistance 28 and condenser 27 passes to the conductor 2, returning over conductor 1, through condenser 26 to ground through resistance 29. When the contacts of relay 6 close, the condensers 26 and 27 discharge in series with the loop over conductors 1 and 2. The fact that the condensers 26 and 27 charge and discharge in series with the line loop insures that the energy in each conductor of the loop will be substantially the same notwithstanding commercial differences in the values of the condensers or the resistances of units 28 and 29 and further, the employment of two resistances 28 and 29 insures substantial symmetry relative to inductive effects on parallel circuits which may be present from any extraneous sources on the two line conductors.

Relay 8 during its energization places a shunt circuit around the upper winding of the retardation coil 25, extending over the inner upper front contact of relay 8, which serves to prevent 135-cycle current from being induced through this coil into the low frequency circuits of the set. This also tends to reduce the impedance of the lower winding of the retardation coil, thereby insuring a maximum of ringing current for steadily retaining the relay 9 operated during the ringing interval.

When a signal is incoming over the line 1-2 relay 6 is energized by the incoming 135-cycle current over a path extending from conductor 1, the upper winding of coil 25, condenser 26, windings of relay 6, the lowermost and innermost lower back contacts of relay 8, thence over line 2. Relay 6 closes a circuit for relay 10 extending from battery, winding of relay 10, resistance 30, middle upper back contact of relay 8, contacts of relay 6, resistance 29 to ground.

50 Relay 10 operates in turn causing the operation of relay 7 to apply low frequency signaling current from the source 5 to the switchboard line 3-4. To insure that relay 10 will be maintained energized during the half cycle periods during which the contacts of relay 6 are opened, a condenser 31 is placed in shunt of the winding of relay 10 and resistance 30. During the reception of 135-cycle signaling current, the condenser 26 in series with the windings of relay 6 forms a negative reactance which in combination with the impedance of the upper winding of coil 25 establishes a condition of resonance for the 135-cycle bridge path of relay 6, while the condenser 27 in bridge

of the windings of relay 6 serves to effect a condition of inverse resonance at this frequency for relay 6.

In the modification of Fig. 4 a single double-wound retardation coil is employed 70 in both the low and high frequency bridges of the set and as a transformer coupling between the vibrator relay 6, when it is serving as a generating device, and the line 1-2. For an outgoing signal low frequency current applied to conductors 3-4 at the switchboard passes from line conductor 4, through relay 9, the upper normal contacts of relay 33, the right winding of retardation coil 35, the intermediate back contact 80 of relay 8, back to conductor 3. Relay 9 responding, closes a circuit extending in parallel through the windings of relays 8 and 33. Relay 8 upon energizing disconnects the limbs of line 1-2 from the talking 85 conductors of the set and prepares circuits for coupling relay 6 to the line 1-2. Relay 33 switches relay 9 to an alternative bridge circuit extending through the upper alternate contact of relay 33 and resistance 34, 90 opens the circuit extending from the winding of relay 10 to prevent its operation at this time, and closes an operating circuit for relay 6 which may be traced from battery, upper front contact of relay 8, left 95 winding of coil 35, windings of relay 6, innermost lower front contact of relay 33 to ground. Relay 6, upon energizing, closes a shunt about its own windings extending 100 from its contacts, middle lower front contact of relay 33, windings of relay 6 to ground at the innermost lower front contact of relay 33. Relay 6 thus operates in a vibratory manner causing surges of current in the left winding of coil 35 which induce current into the right winding of coil 35. The right winding of coil 35 is at this time connected to line 1-2 from conductor 1, through the right winding of coil 35, over 110 the lower front contact of relay 8 to conductor 2. Current of 135-cycles frequency is thus transmitted to the line 1-2, so long as relay 9 remains energized.

At its lowermost front contact relay 33 connects the condenser 37 in parallel with the left winding of coil 35 and the condenser 38 is retained in shunt of one winding of relay 6 to maintain the relay 6 vibratory at the proper frequency during its operation as a generator of high frequency current. Relay 8 also through its lower front contact bridges the condenser 36 around the right winding of coil 35 as an artificial load and surge path.

In response to signals of 135-cycle frequency incoming over line conductor 1, condenser 36, upper normal contact of relay 8, left winding of coil 35, windings of relay 6, innermost lower normal contact of relay 33, lower back contact of relay 8 to con-

ductor 2, relay 6 operates. Condenser 36 at this time serves to effect series resonance of relay 6, while the condenser 37 which is in bridge of the upper winding of relay 6, 5 through the lower back contact of relay 33 and the condenser 38 in shunt of the lower winding of relay 6 serves to effect parallel resonance with respect to relay 6, thus insuring that relay 6 will properly respond 10 to the frequency of the incoming signaling current.

The operation of relay 6, with relay 33 de-energized, establishes a circuit for relay 10 from battery, winding of relay 10, resist- 15 aces 30 and 32, middle lower back contact of relay 33 to ground at the contacts of relay 6. Relay 10 operates being main- tained operated during the half cycles in which the contacts of relay 6 are open by 20 means of the condenser 31 in shunt of its winding. The operation of relay 10 causes the release of relay 24 and the operation of relay 7 to apply low frequency signaling current from the source 5 to the switchboard 25 line 3-4 as previously described.

In Fig. 5 the invention has been further expanded to show a composite set entirely free from external sources of signaling current, two differently tuned vibratory relays 30 being used as generators of, and devices responsive to high and low frequency current, respectively. It will be first assumed that ringing current of 20-cycles frequency is applied to the switchboard line 3-4 and that 35 135-cycle ringing current is to be impressed on the line 1-2. The 20-cycle current entering the composite set by way of conductor 3 flows over the inner upper back contact of relay 7, retardation coil 39, condenser 41, up- 40 permost back contact of relay 7, windings of relay 40, middle lower back contact of relay 7, back over conductor 4. At this time condenser 42 is connected in parallel with the windings of relay 40 over the middle upper 45 back contact of relay 7 for the purpose of establishing a condition of parallel resonance for relay 40 at its control frequency of 20-cycles per second. Reciprocation of the armature of relay 40 in phase with the 20- 50 cycle current, results in the closure of a circuit for relay 8 extending from battery through the winding of this relay, resistance 43, lowermost back contact of relay 7 to ground at the contacts of relay 40. To 55 insure that the relay 8 will be maintained steadily energized during the operation of relay 40, the condenser 44 is connected from the circuit of relay 8 to ground.

Relay 8 upon energizing opens the normal 60 connection of the limbs of line 1-2 with the talking conductors of the set, opens the circuit extending through relay 7 to prevent its operation at this time, and prepares circuits for operating relay 6 as a generating device 65 and for connecting it to the line 1-2. The

energizing circuit of relay 6 may now be traced from battery, through the right wind- 70 ing of transformer 45, the uppermost front contact of relay 8, windings of relay 6 to ground at the middle lower front contact of relay 8. Relay 6 energizes and closes a shunt about its windings, extending from ground at its contacts, the lowermost front contact of relay 8, the uppermost front contact of relay 8, windings of relay 6 to ground 75 at the middle lower front contact of relay 8. Relay 6 thus operates in a vibratory manner, setting up surges of current in the right winding of transformer 45 which are in- 80duced in the left winding of the transformer and transmitted to the line 1-2, over a circuit extending from conductor 1, innermost upper front contact of relay 8, left winding of transformer 45, innermost lower front contact of relay 8, to conductor 2. At its 85 middle upper front contact relay 8 connects the condenser 48 and resistance 46 in shunt of the lower winding of relay 6 to insure that relay 6 when functioning as a generat- 90 ing device shall generate current of the de- sired frequency.

If desired a condenser 49 may be bridged about the major portion of the right wind- 95 ing of transformer 45 for preventing inductive discharges from this winding from reaching the contacts of relays 6 and 40 at the time they are operating as vibrators. The small portion of the transformer wind- 100 ing not encompassed by the condenser, serves to diminish the instantaneous value of the condenser charging current at such instants as the contacts of relays 6 or 40 are closed to ground. This protects the contacts of the relays from excessive currents which may be present when the circuits are 105 designed for heavy current output. This condenser 49 also serves for increasing the output of alternating current and may serve for phase correction in situations where the electrical and mechanical time 110 constants of the circuits and vibrator relays may not be definitely proportioned to the frequency employed. This more partic- 115 ularly concerns conditions of symmetry relative to the duration of the open and closed periods of the contacts of the vibratory re- 120 lays. When properly designed and proportioned electrically and mechanically, how- ever, the closed and opened periods of the vibratory relays may be in such agreement as to result in symmetry with respect to suc- 125 cessive half waves of the alternating current produced without recourse to a condenser as a correcting means.

For signals in the opposite direction with relay 8 deenergized, relay 6 functions as a responsive device being bridged similarly to relay 40 across the line 1-2 through the re- 130 tardation coil 50 and condenser 47, and is operative in response to 135-cycle current

causing the operation of relay 7 and vibrator 40 to transmit 20-cycle current to the line 3-4. The retardation coils 39 and 50 together with the condensers 41 and 47 provide resonating paths of the proper frequencies for relays 40 and 6 when such relays function as responsive devices while presenting paths of high impedance to voice currents.

10 In Fig. 6 the applicant's invention has been shown applied to a standard composite set in which the switchboard line is normally connected with the outgoing line through a high pass filter. When low frequency signaling current of 20 cycles is applied at the switchboard to the line 3-4, this current traverses the upper back contact of relay 7, upper winding of retardation coil 53, condenser 54, relay 9; lower winding of coil 53 and the lower back contact of relay 7 causing the operation of relay 9. Relay 9 upon operating closes obvious circuits for relays 55 and 56, the relay 56 disconnecting the high pass filter 57 from the line 3-4. Relay 55 disconnects the winding of relay 10 from the contacts of relay 6 to prevent its operation at this time, connects the relay 6 to the line 1-2, through the transformer coil 58, and establishes an energizing circuit for relay 6. This energizing circuit may be traced from battery, innermost lower contact of relay 55, upper winding of coil 58, windings of relay 6 to ground at the lowermost front contact of relay 55. Relay 6 energizing in this circuit, closes a shunt about its windings from ground at its contacts, through the middle lower front contact of relay 55, windings of relay 6 to ground at the lowermost contact of relay 55. Relay 6 thus operates in a vibratory manner setting up sponges of current in the upper winding of coil 58 which are induced in the lower winding of this coil and transmitted as 135-cycle alternating current to the line 1-2. The lower winding of coil 58 is at the time connected from conductor 1 to conductor 2, through the upper front contact of relay 55. Condensers 59 in bridge of relay 6 establish a condition of inverse resonance for relay 6 at the frequency of 135 cycles.

When a signaling current of 135 cycles is incoming over line 1-2, with relay 55 de-energized, this current flows from conductor 1 through the lower winding of coil 58, condensers 60, lower back contact of relay 55, windings of relay 6, upper winding of coil 58, upper back contact of relay 55 to conductor 2. Relay 6 in responding to this current closes the circuit of relay 10 extending from battery through relay 10, resistances 30 and 32, middle lower back contact of relay 55 to ground at the contacts of relay 6. Relay 10 operates, being maintained energized during half cycle periods

when the contacts of relay 6 are opened, by the discharge of condenser 31. Relay 10, in operating, shunts the winding of relay 24, which upon deenergizing, closes the circuits of relays 61 and 7 in parallel. Relay 61 70 closes an obvious circuit for relay 56 which disconnects the high pass filter 57, and relay 7 disconnects the relay 9 from the line 3-4 and connects the 20-cycle source of ringing current 5 thereto. The condensers 75 60 included in the bridge circuit of relay 6 serially resonate the circuit of relay 6 so that this relay responds properly to signaling current of 135 cycles. It is to be noted that the retardation coil 58 serves a double 80 purpose, first, to reduce transmission losses during conversation, and secondly, during the transmission of 135-cycle current, as a transformer for connecting the vibrator relay 6 with the outgoing line 1-2.

While the vibratory relay in accordance with applicant's invention has been shown as embodied in several different types of composite sets, it is obvious that a relay of this general type might be employed in circuits of other types for generating or responding to an alternating current at any desired frequency within the mechanical limitations of the relay structure.

What is claimed is:

1. In a telephone exchange system, a line, a relay, means for associating said relay with said line whereby said relay is responsive to signaling current of a predetermined character, and means for altering the association of said relay with said line whereby said relay functions as a vibrator to transmit signaling current of said character out over said line, said relay having short-circuiting contacts for causing its vibratory operation.

2. In a telephone exchange system, a line, a relay, inductive means for associating said relay with said line whereby said relay is responsive to incoming signaling current of a predetermined character, and means for altering the association of said relay with said inductive means whereby said relay functions as a vibrator to generate and transmit signaling current of said character out over said line.

3. In a telephone exchange system, a line, a relay, means controlled over contacts of said relay, a source of current, means for associating the winding of said relay with said line whereby said relay is responsive to incoming signaling current of a predetermined character, and means for switching said relay winding into a circuit with said source of current and the said relay contacts into a short-circuit about the windings of said relay whereby said relay functions as a vibrator to transmit signaling current of said character out over said line.

4. In a telephone exchange system, a line,

- 5 a relay, means controlled over contacts of said relay, a source of current, inductive means, means for associating the winding of said relay with said line whereby said relay
is responsive to incoming signaling current
of a predetermined character, and means for switching said relay winding into circuit with said source and into association with said inductive means and said contacts into
10 a shunt about the winding of said relay whereby said relay functions as a vibrator to generate and transmit signaling current of said character out over said line.

5. In a telephone exchange system, a line, 15 a relay, means controlled over contacts of said relay, a source of current, an induction coil, means for associating the winding of said relay with said line whereby said relay is responsive to incoming signaling current
20 of a predetermined character, and means for switching said relay winding into circuit with said source and said induction coil and said contacts into a shunt about the winding of said relay whereby said relay functions as
25 a vibrator to generate and transmit signaling current of said character out over said line.

6. In a telephone exchange system, a line divided into a first and a second section, means associated with said first section and responsive to signaling current incoming thereover, and means controlled thereby for generating and transmitting signaling current out over the second section of said line, said means comprising a vibrator relay having
35 short-circuiting contacts.

7. In a telephone exchange system, a line divided into a first and a second section, means associated with said first section and responsive to signaling current of one character incoming thereover, a vibrator relay responsive to signaling current of a second character incoming over the second section of said line, a source of signaling current of said first character, means responsive to
40 said relay for applying current from said source to the first section of said line, and means responsive to said first means for generating and transmitting signaling current of said second character out over the
45 second section of said line, said last means comprising said relay and inductive means.

50 8. In a telephone exchange system, a line, divided into a first and a second section, a vibrator relay associated with each section of said line, said relays being adjusted to be responsive respectively to signaling current of different characters incoming over the respective sections of said line, and means for generating and transmitting signaling current of said different characters out over the sections of said line, each of said means comprising one of said relays and inductive means.

9. In a telephone exchange system, a line divided into a first and a second section, and means responsive to signaling current of one character incoming over the first section of said line for applying current of another character to the second section of said line, and vice versa, said means comprising two vibrator relays and inductive means, each of said relays adapted to function either as a responsive device or in conjunction with said inductive means as a current generating device.

10. In a telephone exchange system, a line divided into a first and a second section, a differently tuned relay normally associated with each section of said line, inductive means, and means under the control of each of said relays when responding to signaling current of the frequency to which it is tuned incoming over the associated section of said line for altering the association of the other relay with its corresponding section of the line whereby said latter relay functions in conjunction with said inductive means to generate and transmit signaling current of the frequency to which it is tuned to the associated section of the line.

11. In a signaling system, a line over which signaling current may be transmitted, in both directions, a device responsive at one time as a relay to alternating current flowing over said line from a distant point, and means co-operating with said device to render said device effective at another time as a converter to generate and transmit alternating current out over said line to the distant point.

In witness whereof, I hereunto subscribe my name this 16th day of October A. D., 1924.

HENRY W. O'NEILL.

In witness whereof, I hereunto subscribe my name this 16th day of October A. D., 1924.

HENRY W. O'NEILL.
